UNITED STATES PATENT OFFICE.

LELAND H. HILL, OF SWISSVALE, PENNSYLVANIA, ASSIGNOR TO WESTINGHOUSE ELECTRIC & MANUFACTURING COMPANY, A CORPORATION OF PENNSYLVANIA.

TAP CHANGER.

Application filed March 31, 1926. Serial No. 98,717.

My invention relates to electrical switching mechanisms and particularly to tap changers for transformers or other apparatus.

5 One object of my invention is to provide a tap-changing device that shall be in unstable equilibrium during the operation of tap changing.

A further object of my invention is to 10 provide a tap changer in which the bridging member has a partial turning movement about the stationary contact member that it is facing.

In changing the tap connection of the 15 electrical transformers, it is very important that the service be uninterrupted for the least possible time. It is desirable that a tap-changer shall not remain in a position in which the transformer circuit is incom- 20 plete.

In the accompanying drawings,

Figure 1 is a plan view, partially in section, of a tap-changing device embodying my invention.

25 Fig. 2 is a sectional view taken along the section line II—II of Fig. 1.

Fig. 3 is a plan view of my improved tap changer immediately preceding its transition from one tap connection to another.

30 Fig. 4 is a similar view of the tap changer showing in full lines the position assumed during the first movements of separation of the tap changer, and, in dotted lines, the position assumed at the end of the tap 35 changing operation.

My invention comprises, in general, a pair of base plates 1 of suitable insulating material between which are mounted a plurality of stationary contact members 2, connected 40 to transformer windings (not shown), and arranged in the circumference of a circle. A movable bridging member 3 of arcuate contour is pivotally mounted on support 4, that is, in turn, mounted on a shaft 5 centrally disposed relative to the stationary contact members 2. The bridging member 3 is adapted to engage two adjacent stationary contact members 2 simultaneously.

45 Referring particularly to Figs. 1 and 2, the support 4 comprises a clamp 6 that is mounted about the shaft 5 and which supports a pair of outwardly extending rods 7 between which a coil spring 8 is mounted. A lug 9 extends outwardly from the clamp 6 55 within the convolutions of the spring 8 and

engages a cylindrical member 11, thereby constituting a telescopic connection. The spring 8 presses against a yoke or header member 12 that is slidably mounted on the rods 7. The yoke 12 supports a shaft 13 that, in turn, supports a pair of arcuate members 14 of conducting material that together constitute the bridging member 3. Accordingly, the bridging member 3 is capable of turning relative to the yoke 12, and at the same time the bridging member 3 and the support 4 may be rotated by moving the shaft 5 by a hand wheel, crank, or any other suitable mechanism (not shown).

In the operation of a tap changer embodying my invention, the shaft 5 is turned carrying with it the rods 7 and the bridging member 3, and the surfaces of the members 14 slide along the surfaces of the stationary contact members 2, with which they are engaged. This motion is not a true movement of translation but partakes of a turning movement around a stationary contact member 2 in the direction of movement of the bridging member 3, since the shaft 13 turns relatively to the supporting yoke 12. As the turning movement of the shaft 5 continues, the bridging member 3 shifts from the position shown in Fig. 1, to the position shown in Fig. 3. During this movement, the spring 8 is compressed and the yoke 12 moves inwardly along the rods 7. So long as the spring 8 is under compression, the tap changer is in a state of unstable equilibrium and tends to return to the position shown in Fig. 1.

During the foregoing movement, contact is not broken, between the adjacent stationary contact members 2, although it is to be noted that the motion of the bridging member 3 is relatively slow compared with that of support 4. However, as soon as the shaft 13 crosses the center line of the shaft 5 and one of the stationary contact members 2, the spring 8 expands, thereby causing the bridging member 3 to move rapidly across the surface of the stationary contact member 2 against which it is bearing, and into engagement with the next stationary contact member 2, thereby completing a new circuit.

It will be thus observed that I have provided a tap-changing switch that is in a position of unstable equilibrium when it is not completing the connection between adjacent

stationary contact members. The operation of circuit interruption is relatively slow as compared to the operation of circuit engagement, since compressive forces are stored during the former operation that are liberated to accelerate the latter operation.

It is to be understood that such changes may be made in the details and arrangements of the several parts of my invention as shall fall within the scope of appended claims.

I claim as my invention:

1. In a switch structure, a plurality of stationary contact members disposed substantially in the arc of a circle, a rotatable supporting structure mounted centrally of and wholly within the stationary contact members, and a bridging member for simultaneously coacting with a plurality of said members pivotally mounted on the supporting structure whereby the bridging member has a turning movement about the stationary contact members during its engagement therewith.
2. The combination with a plurality of circumferentially disposed stationary contact members, of an arcuate shaped bridging member and a pivoted support therefor comprising a shaft, guide rods mounted thereon, a coil spring mounted between the guide rods, and a yoke member for pivotally supporting the bridging member and that is mounted on the rods and biased in an outward position by the spring.
3. The combination with a plurality of stationary contact members, of a rotatable member, a second rotatable member carried thereby, and a contact-making member carried by said second named rotatable member for simultaneously coacting with a plurality of said contact members and means for biasing said contact-making member from said first-named rotatable member.
4. The combination with a plurality of

stationary contact members, of a rotatable member, a second rotatable member carried by said first named rotatable member and movable toward and from the same, and a contact-making member carried by said second named rotatable member for simultaneously coacting with a plurality of said contact members.

5. The combination with a plurality of stationary contact members, of a rotatable member, a second rotatable member carried by said first named rotatable member and movable toward and from the same, a contact-making member carried by said second named rotatable member for simultaneously coacting with a plurality of said contact members, and means for biasing said contact-making member toward said contact members.

6. The combination with a plurality of stationary contact members, of a rotatable member, a guide rod carried by said rotatable member, a second rotatable member slideable along said guide rod, a helical spring interposed between said rotatable members, and a contact-making member carried by said second named rotatable member for simultaneously coacting with a plurality of said contact members.

7. The combination with a plurality of stationary contact members, of a rotatable member, a guide rod carried by said rotatable member, a yoke slideable on said guide rod, a second rotatable member carried by said yoke, means for biasing said yoke from said first named rotatable member, and a contact-making member carried by said second named rotatable member for simultaneously coacting with a plurality of said contact members.

In testimony whereof, I have hereunto subscribed my name this 13th day of March, 1926.

LELAND H. HILL.
